[57] CLAIM

The ornamental design for a stem and a base of a bowl of a stemware glass, as shown and described.

DESCRIPTION

FIG. 1 is a perspective view of a stem and a base of a bowl of a stemware glass showing my new design with a bowl being shown in broken lines as illustrative of environmental structure only.

FIG. 2 is a vertical cross-sectional view thereof, along the line 2—2 of FIG. 1; and

FIG. 3 is a horizontal cross-sectional view thereof, along the line 3—3 of FIG. 1.
